(57) **CLAIM**

The ornamental design for a roller shade bracket, as substantially shown and described.

DESCRIPTION

FIG. 1 is a front perspective view of a roller shade bracket showing my new design, the dotted lines depicting environmental subject matter only and forming no part of the claimed design.

FIG. 2 is a front elevational view thereof;

FIG. 3 is a rear elevation view thereof;

FIG. 4 is a left side view thereof;

FIG. 5 is a right side view thereof;

FIG. 6 is a top plan elevation view thereof; and,

FIG. 7 is a bottom plan view thereof.
